UNITED STATES PATENT OFFICE

WILLIAM A. ROSENBERGER, OF HAGERSTOWN, MARYLAND, ASSIGNOR TO PANGBORN CORPORATION, OF HAGERSTOWN, MARYLAND, A CORPORATION OF MARYLAND

SAND BLAST TANK APPARATUS

Application filed August 18, 1928. Serial No. 300,578.

The invention relates particularly to a small sand blast apparatus of the portable type, though the features of the invention are capable of general application.

5 The objects of the invention are to provide the sand blast tank with means for separating the moisture from the air as it enters the tank, the same being preferably so arranged and connected as to be also utilized as a means for 10 separating the abrasive particles from the air when the pressure in the tank is discharged for any purpose, as in refilling with abrasive, and the device may further include means for protecting the separator element from 15 the action of the abrasive as it is projected against the separator by the air as it escapes from the tank through the separator.

The apparatus also includes improved means for controlling the discharge of the 20 abrasive and regulating the abrasive flow with extreme accuracy, the same being adapted to prevent clogging of the abrasive as it passes through the regulating passages or orifices.

In the accompanying drawings:

25 Figure 1 is a side elevation of a small sand blast tank of the portable type equipped in accordance with the invention.

Figure 2 is a top plan view of the same.

Figure 3 is a vertical section through the 30 bottom of the tank and controller valve casting on the axis of the controller valve.

Figure 4 is a section on the line 4—4 of Figure 3.

Figure 5 is a top plan view of the right hand 35 end of the controller valve as seen in Figure 3, the same being shown in this figure as disconnected from the tank.

Figure 6 is a perspective view of the eccentrically apertured valve bushing.

40 Figure 7 is a diagrammatic plan of the abrasive passage and valve, the valve casting being broken away.

Figure 8 is a fragmentary perspective view of the controller valve removed from the 45 valve seat.

Figure 9 is a vertical cross section showing the water and abrasive separator.

Figure 10 is a horizontal cross section on the line 10—10 of Figure 9.

50 Figure 11 is a plan of the controller valve,

the portion at the left being broken away and shown in section on the line 11—11 of Figure 3.

Referring to the drawings by numerals, each of which is used to indicate the same or similar parts in the different figures, the machine, as shown, comprises a sand blast pressure tank 1 which, as shown, is preferably of the small portable variety to which the features of the invention are particularly adapted, though they are capable of more general application.

The tank 1 is provided with a filler valve 2 at the top for the admission of abrasive, air under pressure being supplied by way of an air pressure pipe 3 to the separator 4, which separator 4 is connected by a short nipple 5 to the inside of the tank near the top and by a drop pipe 6 to the abrasive mixing and controlling valve 7 at the side by way of a passage 8, see particularly Figure 4, the controller valve, in turn, being connected in a manner to be described, to the bottom of the tank at 9 to receive abrasive therefrom. The controlling and mixing valve 7 is, in turn, connected by way of a flexible hose 10 to a suitable abrasive projecting nozzle 11.

Referring more particularly to the details of the structure, the valve 2 for the admission of abrasive is, in the preferred form of the invention shown, held in position by a screw handle 15 which has a threaded engagement with a yoke 16, which yoke is removably secured in position on the tank by means of bolts or studs 17 having heads 18 spaced upwardly above the tank, the yoke having open slots to receive the bolts.

The slot 19, Figure 2, in the form of the invention shown, is open at one end of the yoke and the slot 20 is open at the side near the other end. The handle 15 has a screw threaded shank 21 which has a threaded engagement with the yoke and the end of the screw may engage the cover in any suitable manner.

The air pressure pipe 3, in the form of the invention shown, is provided with a three-way valve 25, see Figure 1 which, in the different positions of the valve, connects the pressure pipe 3 to the tank and to the mixer 100

valve 7 through the separator 4 and in the other position of the valve closes the pressure pipe 3 and connects the tank 1 and the mixer valve 7 to the open air by way of the 5 separator 4.

The separator 4 comprises a separator member 27, also referred to as a separator barrel, in the form of a tubular member which, in the preferred form of the invention shown, is composed of several layers of wire cloth. This barrel or separator member, as shown, extends the full length of the separator casing 28. It encloses the end of the air inlet 29 at the top inside the casing 10 28 and the end of the drip discharge 30 at the bottom, the end referred to being also at the inside of the casing. The casing 28, as shown, consists of a tubular member 31 enclosing the separator member. This is closed 15 at the top by a cap 32 through the center of which the connection 29 is passed, and it is closed at the bottom, in the form of the invention shown, by a fitting 33 which may be also referred to in its complete form as a cap, 20 but which, in the form of the invention shown, is a reducing fitting enclosing with its upper portion the lower end 34 of the tubular member 28 of the casing, the said fitting being, in turn, closed at its lower end 25 by a plug 35 which is hollowed out to receive the lower end of the separator barrel 27 and is further bored and tapped at 36 at its lower end at the center to receive the drip cock 37. The separator barrel 27 is encircled opposite 30 the nipple 5 which connects the separator to the tank and the connection 38 which connects the separator to the drop pipe 6 which leads to the mixing valve by a shield shown in the form of a plate ring 39 which protects 35 the separator member or barrel 27 or the wire cloth portion thereof from the abrasive particles which would otherwise be projected against the separator member when the tank is being emptied of compressed air through 40 and by way of the separator, as already indicated and as more fully hereinafter described.

It will be understood that when air is admitted from the pressure pipe 3 through the 50 nipple 29 at the top of the separator, it is discharged within the separator inside the separator barrel 27 and passing outwardly through the multiple screen the moisture is rubbed out of the air by contact with the 55 screen. This effect is increased by the tendency to expansion of the air from the pressure in the pipe 3 to the pressure within the tank 1 causing cooling and condensation. The moisture thus collected runs down inside 60 the tubular separator member 27 and collects at the bottom of the casing 28 in the cap or fitting 33 from which it is removed at the will of the operator by opening the drip cock 37.

65 The reverse operation of the separator is of

considerable importance. When new abrasive is to be supplied the three-way valve 25 is first turned to release the air under pressure in the tank through the opening 26 leading from the valve to the outside air, the 70 pressure pipe 3 is at the same time closed. In passing through the separator, which it enters from the tank mainly by way of the nipple 5, and drop pipe 6 and the fitting 38, the air is projected directly against the shield 39 and owing to the high velocity which it attains and to the boiling of the abrasive in the tank due to the release of the pressure, a considerable amount of abrasive is carried by the escaping air into the separator where it 75 comes in contact with the shield 39 and is deposited in the separator. Part of the abrasive thus deposited is returned to the tank by the reverse air current during the subsequent filling of the tank with air and any which accumulates in the separator may be discharged by way of the bottom plug 35, which 80 may be removed for this purpose.

By the action of the separator 4, removing the abrasive from the air during the discharge of the latter from the tank prior to filling, the destructive action of the abrasive on the three-way valve 25 through which it must pass in the absence of the separator, is practically eliminated and in this way an extremely troublesome source of replacements is removed or, at least, the necessity for replacements is so reduced as to have substantially this effect.

Other features of importance relate to the 90 construction and operation of the mixing and controlling valve and other details at the bottom of the machine which contribute to the production of accurate control and easy adjustment of the stream, making it 95 possible to use extremely fine nozzles down to those as small as three sixty-fourths of an inch. The features of this part of the machine also include an arrangement whereby it is made possible to handle a fine stream of 100 abrasive, as described, without clogging.

The construction also includes a new form of valve which not only contributes to accuracy of adjustment, but to the length of life of the assembled device, in that it not only presents to the abrasive a shut off edge of material which withstands the abrasive action to the best advantage, but provides for four of such edges which can be used alternatively, increasing the life of the valve member by a corresponding multiple. The construction also provides for the instantaneous replace of the valve member.

In the form illustrated, the tank is flanged at the bottom at 40 surrounding the discharge opening 9, the flange being shown as welded to the tank proper and the mixer valve member 41 which comprises the flow control, the abrasive flow valve and the mixer or mixer valve proper is secured to this flange 40 in 115 120 125 130

any suitable manner, as by means of bolts 42 passed through the flange 40 and through suitable ears 43 on the mixer valve member 41, see particularly Figures 1, 3 and 5.

5 In the construction shown the discharge opening 9 is slightly enlarged or chambered at 44 immediately below the mouth of the opening 9 which chamber 44 receives and accommodates the flow control bushing or approach bushing 45, to be more particularly described.

The flange 40 is further chambered at 46 surrounding the chambered portion 44 near the bottom surface of the flange 40. This 15 chamber 46 being wide and shallow to accommodate a gasket 47 between the flange 40 and the controller valve casting 41. The mixer valve casting 41 is provided near the bottom with a longitudinal air passage 48 which, as 20 shown, and normally, is substantially horizontal.

This passage 48 is closed at one end at the left in Figure 3 and at the other end at the right it terminates in the air and abrasive 25 mixture passage 49, which discharges into the hose 10 which is connected to the fitting 50 which is seated in the mouth of the passage 49. Leading downwardly into the abrasive and air mixture passage 49 is the abrasive 30 passage 51 which, in the form of the invention shown, has a reducing taper downwardly toward the passage 49, being intersected by the abrasive flow valve chamber 52, which chamber 52 is shown in the form of a horizontal bore formed in the mixer valve member 41 which it enters from the left of the same, as seen in Figure 3. Above the valve chamber which releases the pressure from the 35 particles immediately below the chamber 52 the abrasive passage 51 has a reducing taper upwardly to the flow control chamber, the lower portion 53 of which is formed in the upper portion of the mixing valve casting, the other portion of the chamber, indicated 40 by reference character 44, being formed in the flange 40 at the bottom of the tank 1.

The abrasive control valve 55 which operates in the chamber 52 is a cylindrical tubular member, preferably formed, particularly 50 as to its wearing surface, of high quality rubber. This valve is secured to a valve operating shaft 56 which fits inside of the tubular valve member 55, being secured thereto to rotate therewith by means of a pin 57 which 55 extends diametrically through the shaft and through the tube.

The valve and shaft are surrounded near the open end of the chamber or bore 52 by packing 57, which is separated from the tubular valve member 55 by washers 58. The packing and the valve and the shaft are, in turn, held in position by the packing gland member 59 which is shown in the form of a hollow plug which is apertured at 60 to pass 60 the shaft 56. The gland member 59 is shown

as provided with laterally extending arms 61, see particularly Figure 4, through which are passed bolts 62, see Figures 3 and 4, which bolts are seated in the valve member 41 at each side of the bore 42. The gland member 70 59 enters the end of the bore 52, being forced into close contact with the packing and compressing the same by tightening of the bolts 62. The shaft 56 may be turned by means 75 of an indicating wheel 64 which is secured to the end of the shaft in any suitable manner, as by means of a pin 65, the wheel being preferably marked with graduations 66, see Figure 1, which cooperate with an indicating pointer 67 on the valve member or casting 41 80 and the graduations 66 are preferably arranged in four series or scales on each side of two zero marks 74 indicating the two closed positions of the valve, as hereinafter described. 85

The valve member 55 is preferably slotted at 70, the slot being adapted to register in the open position of the valve with the passage 51 formed in the casting 41 for this purpose, it being understood that the valve seat chamber 52 intersects the passage 51 and divides it into upper and lower portions or openings 51' and 51''. By rotating the valve 90 55 to the position in which the slot 70 registers with these openings, a passageway for 95 the abrasive is opened from the tank 1 to the mixture or mixing passage 49.

In accordance with the preferred construction the slot 70 is of the V type, or otherwise formed to present one or more inclined closing edges 72. In the form of the invention shown, there are four of these edges, two being presented at each of the opposite ends of the V shaped slot 70. 100

As will be noted from examination of the 105 diagrammatic view, Figure 11, the passage 51 is preferably of rectangular cross section, being shown as elongated so that the initial opening formed by the intersection of the edges 72 with the cross section of the passage 110 110 is triangular, as illustrated diagrammatically in Figure 7 by dotted lines 73.

This illustration shows a distinct advantage incident to the inclined closing edges, particularly in connection with the rectangular passage 51 having two sides parallel to the axis of the valve and two sides at right angles to it, in that it gives extremely fine regulation or adjustment as compared to 115 would be given by closing edges parallel to the sides of the passage 51 which, in the initial opening which would otherwise be the extreme minimum of adjustment, would give a narrow slot. Such a slot when of less width than the particles of abrasive would admit 120 no abrasive at all and when opened to a sufficient extent to pass the abrasive will pass a larger quantity than is desirable for the minimum adjustment, whereas in the operation 125 of the construction shown in Figure 11, the 120

initial opening being triangular in outline, can be adapted to pass an extremely small quantity of abrasive, the adjustment being capable of reduction to a point where a single

5 line of abrasive particles is passed through the opening at the minimum adjustment.

The construction shown, particularly in Figure 8, attains the extremely important result that it presents four closing edges 72, 10 either one of which may be passed across the opening 51 ahead of the remainder of the valve, in the opening or closing operation.

It will be easily understood that in the operation of this valve there are two fully closed 15 positions one hundred and eighty degrees apart. By marking these zero points at 74 on the scale 66 and graduating the scale on four quadrants, i. e., on each side of each of these opposite marks 74, a set of graduations 20 is provided corresponding to each of the edges 72 whereby either of them may be used as the advance closing edge in opening and closing the valve and its position, i. e., the degree of opening of the valve may be indicated on the 25 scale by means of the pointer 67.

The flow control bushing or approach bushing 45, previously referred to as seated in the chamber 44, 53, is, in the form shown, provided with a passage 75 which at the top registers with the opening 9 and which terminates at the bottom in a relatively small eccentrically located discharge opening 76. The bushing, see particularly Figure 6, is formed with diametrically opposite key 30 notches 77 which are adapted to engage the key projection 78 on the valve member 41 so that the bushing can be seated in two diametrically opposite positions of adjustment, being raised for which purpose the member 35 41 must be disconnected from the tank 1 and rotated through an angle of one hundred and eighty degrees from one position to the other.

In the position shown, the discharge opening 76 is spaced by about one-third of the 45 diameter of opening 76 out of registration relatively to the passage 51 and in the opposite position in which the other notch 77 engages the key projection 78, the discharge opening 76 will register accurately with the 50 passage 51. This gives what may be termed a primary flow control of the abrasive from the tank 1 to the valve.

A further object of the construction shown as to the bushing 45 and the passage there-through, consists in the means for preventing clogging of the opening 76, 51, by and with abrasive. This is accomplished by making the incline of the tapered passage 75 steeper on one side, i. e., at 79, than it is on the other 55 side at 80 whereby the particles approaching the discharge opening 76 are given a different rate of speed, i. e., faster on the side 79 and slower on the side 80, so that the tendency to clog is overcome by the tendency thus created to rotate the particles on one side

about the particles on the other side. The rolling or rotating effect thus accomplished prevents, or greatly reduces, the tendency to clog the opening.

The operation has been quite fully explained in connection with the description of the machine. When air is admitted to the tank from the pressure pipe 3 the moisture is removed by rubbing as the air expands or passes outwardly through the multiple screen 75 27, entering the tank by way of the connection 5 and being supplied to the mixer valve by way of the drop pipe 6 and lateral passage 8, Figure 4, leading to the air passage 48 and the mixing passage 49.

An important result is attained when the air is discharged from the tank to reduce the pressure therein in order to admit a new supply of abrasive. For this purpose the three-way valve 25 is turned to a position in which the top of the separator is connected by the passage 29 and a portion of the pipe 3 to the outside air by way of the three-way valve, the pressure side of the three-way valve 25 being closed. This causes the air to leave the tank by way of the passage 5, the air from the tank being discharged into the separator against the shield 39 by way of the fitting or nipple 5. A considerable amount of abrasive is carried by the air which is thus discharged, due to the boiling of the abrasive in the tank incident to the drop of pressure therein. This abrasive is separated from the out-flowing air by the separator barrel 27 so that air which is practically free of abrasive is discharged by way of the fitting 29 to the air pressure pipe 3, being released through the three-way valve 25.

An important difficulty with this type of apparatus in the past has resulted from the quick destruction of the three-way valves due to the necessity for passing abrasive through it when the tank was emptied of air. This difficulty is completely overcome by the use and arrangement of the separator in the manner described.

Regarding the control valve mechanism, the flow is controlled primarily by the adjustment of the flow control bushing 45. In this way the discharge opening 76 of the bushing is either placed in registration with the passage 51, giving the maximum flow, or it is placed off-center, as shown in Figure 3, whereby the flow of abrasive is reduced in the first instance to about fifty percent of the maximum, depending on the adjustment of the abrasive flow valve 52 to be most used.

The effect of the variation of incline on the different sides of the opening 75 in the bushing and 79 and 80, has been fully explained 125 whereby the particles on the opposite sides are given different speeds as they descend, which has the effect of rotating the particles one about the other, largely if not fully overcoming any tendency to clog.

The fine adjustment of the abrasive stream, or more particularly of the supply of abrasive fed to the mixing valve to be mingled with the air blast, is obtained by means of the 5 abrasive flow valve 52 which also serves as a shut-off valve to give a complete cessation of the supply of abrasive and a double seal of the passage 51.

In either one of the zero positions, i. e., 10 when either of the zero points 74 on the indicator wheel 64 is in line with the pointer 67, the valve is completely closed and the valve opening, and hence the supply of abrasive passed through the valve, is indicated with 15 exactness by one of the four sets of graduations 66 reading on each side of the two zero points.

The advantages of the four closing edges for alternate use giving, in effect, four operative valve surfaces instead of one, and of the inclination of the valve edges to the rectilinear sides of the passage 51, giving a triangular initial opening in place of an elongated slot with a resulting fine regulation of the 25 stream at and near the minimum flow, has also been fully explained.

Still another important point resides in the easy and convenient manner in which the valve may be removed and replaced. This is 30 accomplished by removing the bolts 62 which hold the packing gland 59 around the valve shaft 56 when the valve with the packing 57 and the shaft 56 may be removed. A new valve may be immediately substituted on the 35 shaft 56 by removing the pin 57, and the new valve as instantaneously replaced.

I have thus described specifically and in detail a sand blast apparatus embodying the features of my invention in the preferred 40 form in order that the nature and operation of the same may be clearly understood, however, the specific terms herein are used descriptively rather than in a limiting sense, the scope of the invention being defined in the 45 claims.

What I claim as new and desire to secure by Letters Patent is:

1. The combination with a sand blast tank of a mixing valve, a passage connecting the 50 tank to the valve to supply abrasive to the valve from the tank by gravity, a tapered bushing having an eccentric opening forming part of said passage the bushing having a restricted area about its bottom portion, 55 means for relieving the pressure on the particles immediately below said restricted area, means for positively locating the bushing in a plurality of positions whereby the relation of the passage in the bushing to the remainder 60 of the passage is varied varying the size of the opening and regulating the flow of abrasive from the tank to the valve and a separate control valve for further determining and regulating the supply of abrasive to 65 the mixing valve.

2. The combination with a sand blast tank and an abrasive mixing valve with a passage leading the abrasive from the tank to the valve by gravity, a bushing having an opening with a downwardly reducing taper forming part of said passage, the lower end of the opening being eccentrically located, the tapered portion having a steeper angle of inclination at one side than the other, and means for locating the bushing in a plurality of positions, varying as to angularly of the bushing about a vertical axis, in one of which the lower end of the opening in the bushing registers with the remainder of the passage more nearly than in another position, whereby the effective size of the opening and the flow of the abrasive may be regulated. 70

3. The combination with sand blast tank and an abrasive mixing valve, the structure including a passage leading the abrasive from the tank to the valve by gravity, the passage comprising a stationary restricted opening and a bushing having an opening with a downwardly reducing taper, the lower end of the opening being eccentrically located and the tapered portion having a steeper angle of inclination at one side than the other, and means for locating the bushing in a plurality of positions in one of which the lower end of the opening in the bushing registers with the restricted opening more nearly than in another position whereby the effective size of the opening and the flow of the abrasive may be regulated, the variation of the incline tending to prevent clogging of 95 the opening. 90

4. The combination with a sand blast tank of a mixing valve and a passage leading abrasive from the tank to the valve and means for regulating the flow of abrasive through the passage comprising a cylindrical valve member of rubberlike material, a cylindrical seating chamber intersecting the passage, so that the plug extends transversely to said passage, means adapted for manual engagement to rotate the valve member at the will of the operator, the end portion of the valve occupying the portion of the chamber which intersects the passage and said portion of the valve having a V slot, which in one angular position of the valve registers with the passage, in which position the valve is open, the V slot in another position of the valve standing at right angles to the direction of the passage in which position the valve is closed, the intersection of the V slot with the cylindrical surface of the valve providing four inclined edges, either one of which may be advanced across the passage to regulate the size of the same. 105

5. The combination with a sand blast tank and a mixing valve, the construction including a passage leading abrasive from the tank to the mixing valve of means for regulating the flow of abrasive comprising a section of 110 115 120 125 130

cylindrical tubing of rubberlike material, a cylindrical seating chamber intersecting the passage, the tubular section fitting the said chamber which is arranged so that the tubular section extends transversely of the passage, means adapted for manual engagement to rotate the valve member, said manually engageable means having a pin adapted to enter the tubular section axially from one end, said pin being provided with means for fastening the tubular section and positioning it against rotation relatively thereto, causing it to rotate therewith, the end portion of the valve opposite to the manually engageable member which occupies the portion of the chamber which intersects the passage having a V slot which in one angular position registers with the passage in which position the valve is open, the V slot in another position of the valve extending at right angles to the position of the passage; in which position the valve is closed, the intersection of the V slot with the cylindrical surface of the valve providing four inclined edges either one of which may be advanced across the passage to regulate the size of the same.

Signed by me at Hagerstown, Maryland,
this 27 day of July, 1928.
